(57) **CLAIM**

The ornamental design for a mobile phone stand with speaker, as shown and described.

DESCRIPTION

FIG. 1 is a top perspective view of a mobile phone stand with speaker, showing my new design;

FIG. 2 shows the mobile phone stand with speaker in a closed configuration;

FIG. 3 is a bottom perspective view thereof;

FIG. 4 shows the mobile phone stand with speaker in an open, extended configuration;

FIG. 5 is a front view thereof;

FIG. 6 is a rear view thereof;

FIG. 7 is a left side view thereof;

FIG. 8 is a right side view thereof;

FIG. 9 is a top view thereof; and,

FIG. 10 is a bottom view thereof.

The broken lines in the drawings illustrate the portions of the mobile phone stand with speaker, which form no part of the claimed design.

1 Claim, 10 Drawing Sheets
